BURNER STRUCTURE

Best Pratt, Chicago, Ill., assignor to Brake Equipment & Supply Company, Chicago, Ill., a corporation of Illinois

Original application December 29, 1938, Serial No. 248,337. Divided and this application March 27, 1941, Serial No. 385,573

3 Claims. (Cl. 158—115)

The present invention relates to a burner structure for gas ranges, the application being a division of my application for Gas range structures, Serial No. 248,337, filed December 29, 1938, issued November 3, 1942 as Patent No. 2,300,961.

The principal objects of the invention are to provide a novel form of burner producing a very efficient flame and which can be very economically manufactured.

Other objects and advantages of the invention will be apparent from the following specification and drawings, wherein:

Figure 1 is a plan view of a gas range burner box fitted with devices of the present invention.

Figure 2 is a side elevation of the structure shown in Figure 1.

Figure 3 is a vertical sectional view on the line 3—3 of Figure 2.

Figure 4 is a plan view of a front and rear burner assembly.

Figure 5 is a vertical sectional view, its upper portion being taken on the line 5—5 of Figure 4 and its lower portion being taken on line 5a—5a of Figure 4.

Figure 6 is a vertical sectional view on the line 6—6 of Figure 4, and

Figure 7 is a vertical sectional view on the line 7—7 of Figure 4.

The structure for use in a gas range burner box illustrated in Figures 1 and 2 includes front burners 8 and 9 and rear burners 10 and 11. The front burner 8 consists of a single main burner head 12 which receives a mixture of gas and primary air through a single mixing tube 13. The front burner 9 is a double burner and comprises a main burner head 12 and a simmer burner head 14, each of which burner heads is adapted to receive gas and air through a separate passage in a double mixing tube 15. The two rear burners 10 and 11 are both double burners, burner 10 consisting of a main burner head 12 and a simmer burner head 14, each of which separately receives gas and air through a double mixing tube 16. Rear burner 11 comprises a main burner head 12a and a simmer burner 14, main burner 12a being of a form slightly different from the main burner head 12.

The burners of the present invention receive gas and primary air through the mixing tubes referred to above, and which are disclosed in detail in my divisional application entitled Mixing tube structure, Serial No. 385,572, filed of even date herewith. The mixing tubes receive gas from the valve structures generally designated

by the numeral 140 and which are fully disclosed in the above-mentioned original application.

The three main burner heads 12 used in the front burners and one rear burner of the Figure 1 assembly are of the construction illustrated in vertical section in Figure 5. As shown in the latter figure, each head 12 includes a base plate 18 and a burner body 19. The base plate 18 is in the form of a flat ring including a downwardly thickened portion or boss 20 adapted to bear upon the upper surface of a mixing tube as hereinafter described. The burner body 19 is annular and of generally inverted U-shaped form in radial section with the outside surfaces of its lower edges of such diameter that it will overlie and fit upon the upper surface of the base plate 18. The outer circumferential wall 22 of the burner body 19 is inclined slightly inwardly from its lower edge and is inwardly offset nearer its upper portion to provide a rounded shoulder 23. Jet ports 24 are circumferentially spaced about the outer wall 22 in a single line and immediately above the offset and rounded shoulder 23. Each of these ports extends through the wall 22 at an angle of about 10° above the horizontal, with the outer or jet end uppermost.

The inner wall 25 of burner body 19 is substantially straight to a point approximately midway of its height and merges into an outwardly curving portion 26 which forms the upper portion of the burner body and joins the rounded upper portion of the outer wall 22. By the above arrangement, any substance which may drop upon the upper portion of the burner during cooking will usually be directed down the inner and blank wall 25 thereof so as not to clog the burner jet ports 24. Because of the steepness of the outer wall 22, any substance which might move down the same will move directly past the jet ports 24. The slight upward inclination of the jet ports 24 will cause the ring of flame formed by the same to be of proper diameter and to extend upwardly about the periphery of the burner.

As best shown in Figure 1, outwardly extending securing lugs 28 are circumferentially spaced about the lower edge of the outer wall 22 of each burner body 19, the lugs 28 being arranged to be aligned with lugs 29 which project outwardly from the burner base plate 18 as indicated in Figure 2. The lugs 29 on the burner plate are threaded to receive a machine screw 30 in a manner similar to that illustrated in Figure 6.

As shown in Figure 5, each burner base plate 18 has an opening 35 extending through its thickened portion or boss 20 and through which gas may

flow into the burner. This opening, illustrated in plan by dotted lines in Figure 2, is of such outline as to be a portion or segment of an annulus.

If the burner is intended to be lighted by a pilot light or from a simmer burner, a radial slot 36 (Figure 5) is provided in the base plate 20, preferably substantially diametrically opposite the gas supply aperture 35, and the outer wall 22 of the burner body 19 associated therewith is similarly slotted as at 39. By this arrangement, when gas issues from the burner jet ports 24 of the burner body, it will also issue from the aligned slots 36 and 39 which, in effect, form a single long slot 41. Ignition of the gas issuing from such slot will result in a flame which will extend up the side of the burner body to ignite the gas issuing from the burner jet ports 24.

The mixing tube 13 which delivers gas and air to the single-type burner 8, in the lower left-hand portion of Figure 1 is described in detail in my above-mentioned divisional application.

The other front burner illustrated in Figure 1; namely, the burner 9, includes an annular main burner head 12, including a burner base plate 18 and a burner body 19, such as shown in detail in Figures 5 and 6 in connection with the burner 9 of Figure 4. The burner 9 also includes a central simmer burner head 14. Main burner head 12 and simmer burner head 14 are fitted upon a double mixing tube 15 of the type disclosed in detail in my other above-identified divisional application, and comprising a main burner mixing tube or passage 13a and a passage 75 leading to the seat for the simmer burner 14 as best shown in Figures 5 and 6. Throughout the greater portion of its length, the passage 75 extends parallel with the passage 13a leading to the main burner, but just forwardly of the outlet chamber 54a of the passage 13a, the passage 75 is directed outwardly at right angles and opens through a port 76 to an open ended chamber 77 having an inwardly projecting annular flange 78 at its lower end. The inner edge of flange 78 is threaded to receive the lower and threaded end 79 (Figure 5) of a simmer burner cap 80.

As shown in Figure 5, the simmer burner cap 80 is of sleeve form and includes an outwardly extending flange 81 at its upper end having ports 82 circumferentially spaced about the same to form upwardly directed simmer flame-jets. The jet apertures 82 are inclined very slightly outwardly from the axis of the cap 80 to spread the ring of flame produced thereby. Gas entering the chamber 77 will circulate between the wall of the chamber and the sleeve portion of the jet cap 80 and move upwardly through the jet ports 82.

It will be noted from Figure 5 that the jet ports 82 of the simmer burner are positioned very slightly below the lower edge of the lower surface of the base plate 18 of the annular main burner 12, and that the outer vertical wall of the chamber 77 is spaced well within the inner wall 25 of the main burner. Thus, the simmer burner 14 will receive an adequate supply of secondary air, this supply being further assured by the construction of the double mixing tube best shown in Figures 4 and 5, whereby upward movement of air about the simmer burner 14 is only prevented in the area occupied by the right angled portion of the mixing tube 15, and by the tongue 84 which may be provided in casting to connect the chamber 77 to the forward wall of the outlet chamber 54a of the mixing tube 15. The annular form

of the simmer burner further assures an ample supply of secondary air through its central passage.

The fact that the simmer burner cap is spaced inwardly from the inner wall 25 of the annular main burner prevents any substance which might flow down along the wall 25 from dropping upon the jet plate of the simmer burner. It will also be noted from Figure 5 that the simmer burner jet plate is above, or bears on, the mixing tube top wall, so that any substance which might drop from the inner wall 25 of the main burner and onto the upper wall of the mixing passage 15 or the tongue 84 will flow off these surfaces and will not flow into the simmer burner jet ports.

The manner of securing a rear main burner 12 and a simmer burner 14 to the mixing tube 16 will be apparent from the above description of the front burner 9.

The double burner 11 shown in the lower right-hand portion of Figure 1 differs from the rear double burner 10 shown in the upper right hand portion of this figure only in that the main burner body 19a included in burner 11 is designed to produce a smaller flame than the burner body 19 of burner 12.

As shown in side elevation in Figure 2 and in cross-section in Figure 3, the outer wall 22a of burner body 19a of burner 12a curves or bends inwardly from its lowermost portion and forms a shoulder 23a intermediate the height of the burner. From this point upwardly, the wall 22a is substantially vertical and merges with the inner wall 25a which curves downwardly to a vertical portion 26a. The jets 24a of the burner body are positioned above the shoulder 23a and since this portion of the burner body is of reduced diameter, the flame produced may, with usual gas flow adjustment, be somewhat lower in B. t. u. output than the burner body 19 of Figure 5. For example, the burner body of Figure 5 may be operated with an output of 12,000 B. t. u., whereas the burner body 12a of Figure 3 may be used for a 9,000 B. t. u. output. It will be noted that since the burner bodies 19 and 19a are of the same dimensions and shape at their lower edges, both bodies may be applied to similar base plates 18. In other words, the burner body 19a will be provided with laterally extending lugs 28 spaced to fit upon the lugs 29 of a base plate 18. In this way, burner bodies of different capacities may be readily fitted upon similar base plates.

In both forms of burner bodies there is an enlargement in radial section below the burner jet ports, and this enlargement, taken with the curvature, in radial section, of the top portions of the burner bodies, results in a better mixing of air with the gas, and better combustion.

Each of the main burners 12 and 12a is fitted with a slot 41 formed by slots 36 and 39 of the type illustrated in Figure 5 so that these burners may be ignited from a flame produced by their corresponding simmer burners 14. The simmer burners are adapted to be ignited from a pilot burner 120 which receives gas through a suitable supply line 121 extending from the gas stove manifold 122. The pilot burner 120 extends upwardly into a housing 123 which is open at its upper and lower ends. Flame-conducting tubes 124 fixed to housing 123 radiate from the latter, one extending to burners in the range burner box. The manner in which a flame conducting tube 124 communicates with a double burner is best shown in Figure 6 and, as there indicated, the

open end 125 of the flame-conducting tube is positioned directly in alignment with a small aperture 126 in the outer wall of the simmer burner. By this arrangement when gas flows to the simmer burner, a portion of the gas will be directed through the aperture 126 to the adjacent end 125 of the flame-conducting tube 124. The gas moving through the latter tube will be ignited at the pilot burner 120 and the resulting flame will issue from the outer end of tube 124 to ignite the gas issuing from the simmer burner jets 82. If the gas-controlling valve has been or is then operated to deliver gas to the main burner, some of the gas entering the main burner will flow from the slot 36 in the burner base plate 18 and be ignited by the simmer burner, this flame moving up the slot 41 to ignite the gas issuing from the ports 24 of the main burner. As shown in the burner structure 9 in the upper left-hand portion of Figure 1, the igniting slot of a main burner is positioned substantially diametrically opposite the igniting port 126 of a simmer burner.

If a burner comprises only a main burner section, as is the case with the burner 8 at the lower left-hand portion of Figure 1, the burner body 19 is so positioned upon the gas mixing tube 13 that the igniting slot 38 thereof will be directly opposite the outer end of the adjacent flame-conducting tube 124. Thus, when gas flows to the single main burner comprising the burner 8, some gas will issue from the slot to be ignited by the flame-conducting tube 124 in the manner described above, and the main burner will thereby be ignited.

Figure 4 shows a front and rear assembly of double burners, of the type described in connection with Figures 3, 5 and 6, the front burner being connected to a double air mixing tube 15 and the rear burner being connected to a double mixing tube 16. The two mixing tubes receive gas from a manifold and valve structure 140 provided with two double valves. A pilot burner 120a is positioned centrally of a pilot housing 123a which includes a flange 145 whereby it may be bolted to the top surface of the double mixing tube 16 as shown in Figure 7. A pair of flame-conducting tubes 124 project to the two burners to ignite the same in the manner described above in connection with Figures 1 and 2.

The installation shown in Figure 4, comprising two burners, and one or both of which may be single burners, is particularly adapted for use in a burner box of the type of range which has a burner box at each end thereof and with the oven between the two burner boxes. Obviously an installation such as illustrated in Figure 4, and including the manifold structure 140, can be fitted to each burner box of this type of range.

The terminology used in the specification is not 60

intended to limit the invention, the scope of the invention being indicated in the following claims.

I claim:

1. A gas burner of annular form including a bottom wall and outer and inner walls defining an annular gas chamber, a circular series of jet ports in the outer upper portion of the wall, said bottom wall having a radial slot extending to its outer edge and opening into the gas chamber, 5 said outer wall having a vertically extending slot in alignment with the slot in the bottom wall and also opening to the gas chamber, the slot in said outer wall terminating below the jet ports so that ignition of gas issuing from the aligned slots will provide a flame to ignite gas issuing from the jet ports.
2. In a gas range burner structure, an outer main burner of annular form to define a central opening, a simmer burner below the central opening defined by said main burner and of a diameter substantially corresponding to that of the main burner central opening, the simmer burner being provided with vertical jet ports to direct a flame within the central opening and having a horizontally disposed ignition port therein to direct gas to an ignition tube, the ignition port being below the vertical jet ports so that a flame created at the ignition port will ignite gas issuing from the vertical ports, the main burner 20 having ports in its outer wall and so disposed that gas issuing therefrom will not be ignited from the ports of the simmer burner, the main burner having a slot in its lower and outer portions spaced circumferentially from the simmer 25 burner ignition port so that gas issuing from the slot will be ignited by a flame at the vertical jet ports of the simmer burner to thereby ignite the ports of the main burner.
3. In a gas range burner structure, an outer 30 main burner of annular form to define a central opening, a simmer burner below the central opening defined by said main burner and of a diameter substantially corresponding to that of the main burner central opening, the simmer burner being provided with vertical jet ports to direct a flame within the central opening and having an ignition port therein to direct gas to an ignition tube, the ignition port being below the vertical jet ports so that a flame created at the ignition 35 port will ignite gas issuing from the vertical ports, the main burner having ports in its outer wall and so disposed that gas issuing therefrom will not be ignited from the ports of the simmer burner, the main burner having a slot in its lower and outer portions spaced circumferentially from the simmer 40 burner ignition port so that gas issuing from the slot will be ignited by a flame at the vertical jet ports of the simmer burner to thereby ignite the ports of the main burner.
4. In a gas range burner structure, an outer 45 main burner of annular form to define a central opening, a simmer burner below the central opening defined by said main burner and of a diameter substantially corresponding to that of the main burner central opening, the simmer burner being provided with vertical jet ports to direct a flame within the central opening and having an ignition port therein to direct gas to an ignition tube, the ignition port being below the vertical jet ports so that a flame created at the ignition 50 port will ignite gas issuing from the vertical ports, the main burner having ports in its outer wall and so disposed that gas issuing therefrom will not be ignited from the ports of the simmer burner, the main burner having a slot in its lower and outer portions spaced circumferentially from the simmer 55 burner ignition port so that gas issuing from the slot will be ignited by a flame at the vertical jet ports of the simmer burner to thereby ignite the ports of the main burner.

BEST PRATT.
